DESIGN FOR A MEDICINE APPLICATOR OR SIMILAR ARTICLE

Ray S. Anderson, Bessemer, Ala.

Application May 28, 1945, Serial No. 119,759

Term of patent 7 years

(Cl. D83—1)

To all whom it may concern:

Be it known that I, Ray S. Anderson, a citizen of the United States, residing at Bessemer, in the county of Jefferson and State of Alabama, have invented a new, original, and ornamental Design for a Medicine Applicator or Similar Article, of which the following is a specification, reference being had to the accompanying drawing, forming part thereof.

Figure 1 is a top plan view of a medicine applicator, or similar article, showing my new design,

I claim:

The ornamental design for a medicine applicator or similar article, as shown.

RAY S. ANDERSON.
